CLAIM

The ornamental design for a planter, as shown and described.

DESCRIPTION

FIG. 1 - is a perspective view of a planter showing my new design;

FIG. 2 - is a top plan view thereof;

FIG. 3 - is a bottom plan view thereof;

FIG. 4 - is a left side elevation view thereof;

FIG. 5 - is a right side elevation view thereof;

FIG. 6 - is a front elevation view thereof; and,

FIG. 7 - is a back elevation view thereof.

The broken lines depict environmental subject matter only and form no part of the claimed design.
